SECURING DEVICE

Lou Obstfeld, Brooklyn, N. Y.

Application May 12, 1931, Serial No. 536,724

10 Claims. (Cl. 1—56)

This invention relates to securing devices.

Particularly, the invention has reference to the assembly into a substantially rigid unit of a plurality of securing devices, all of a particular shape, as hereinafter more clearly set forth. These devices are arranged in contiguous relationship, and are disposed adjacent each other in such manner that an adhesive, applied to the devices, becomes positively effective to retain the devices fixedly relatively to each other, and to the series.

In order to dispose securing devices in the manner set forth, it has been found, for the purposes of this invention, that it is necessary to relate them to each other so that a substantial pocket is produced adjacent the side faces of the devices. This has been accomplished by wracking, or in the broad aspect of the invention, by disposing the devices so that the front faces of the bodies of the devices will be obliquely disposed relatively to any plane intersecting all of the devices at substantially the same point in each of them, or to a plane passed through the extreme edge portions of such devices, or so that planes which are perpendicular to the contact surfaces or lines of adjacent articles will be disposed obliquely to lines or planes intersecting the side edges of the devices at substantially the same point or position in each of said devices.

In my co-pending application, Serial No. 436,682 filed March 18, 1930, which has matured into Letters Patent No. 1,811,060, granted June 23, 1931, this invention has been shown applied to staples, and more especially, to U-shaped staples. Herein it is intended to disclose and claim the invention generically as applied to many other forms of securing devices. Furthermore this invention is not intended to be limited in its scope merely to the disposition of the devices in wracked, or in the specific relation set forth in that co-pending application; it may also have relation to the arrangement of devices of this character whereby substantial pockets are formed or where they already exist they are increased in size at the faces or edges of the devices for the reception therein of adhesive, applied thereat. Due to the greater surfaces provided by these pockets, as against the surface of the edges themselves, a firmer association of the devices with each other will necessarily result.

The apparatus, herein set forth, is intended to cooperate with series of securing devices, arranged in the manner specified, so that, even

though such devices may be disposed at angles considerably beyond the normal angle at which devices of this character are intended to enter the medium with which they are to be associated, still the apparatus will be operative to dispose such securing devices in the preferred relation to such medium, without any marked interference with the apparatus or the medium operated upon.

Other objects of this invention will be apparent from the description and the drawings which form a part of this specification or will otherwise be indicated herein specifically.

The invention, however, is not intended to be restricted to the particular articles of manufacture, nor to construction and arrangement of parts of apparatus, nor to the particular applications of such apparatus, as herein shown and described, nor to the specific methods of operation, nor to the various steps or details thereof, as the same may be modified and applied in various relations, without departing from the spirit and scope of the invention, practical embodiments of which have been herein illustrated and described without attempting to show all the various forms and modifications in which the invention might be embodied.

On the accompanying drawings, wherein are disclosed apparatus and articles of manufacture embodying the invention,

Fig. 1 is a view in perspective of a plurality of glazier's points arranged according to the invention. Of course, it will be understood that while as shown the staggering has been in one direction only, that the individual units could themselves be positioned so that a plurality of series of pockets could be provided.

Fig. 2 is a plan view of the arranged points.

Fig. 3 is a view in perspective of a plurality of brads arranged in similar fashion.

Fig. 4 is a bottom plan view of the arranged brads.

Fig. 5 is a vertical longitudinal sectional view of a machine for driving elements of the character shown, parts being shown in elevation, and a part of the base being shown as if the section line passed as indicated by the line 5—5 in Fig. 12.

Fig. 6 is a plan view of the arm of the machine, parts being broken away in section to clarify the construction.

Fig. 7 is an end elevational view of the arm and plunger casing, the plunger having been removed.

Fig. 9 is a sectional view of the machine arm taken on line 9—9 of Fig. 5.

Fig. 10 is a view in perspective of the pusher element.

5 Fig. 11 is a sectional view on the line 11—11 of Fig. 12.

Fig. 12 is a detail plan view.

10 Figs. 13, 14, 15, 16 and 17, respectively, depict several of the types of assembled units contemplated herein. Where I have referred to "mean plane" of the body herein, I wish to be understood as referring to the following planes, for example:

15 In Fig. 13 to a plane passing through A and B and parallel to face C.

In Fig. 14 to a plane passing through D and E and parallel to face F.

In Fig. 15 to a plane passing through G and H and parallel to face J.

20 20 In Fig. 16 to a plane passing through K, L and point M.

In Fig. 17 to a plane passing through N and Q and parallel to face P.

25 On the drawings, an attempt has been made to disclose the invention as applied to various types of securing devices. However, it is not intended that this disclosure be taken as all inclusive, as the invention may be applied to many classes of securing devices other than those herein shown or described.

30 For the purpose of setting forth clearly and concisely one embodiment whereby the invention may be effected, the construction, shown in Figs. 1 and 2, is taken as an example. In that particular case, a plurality of individual glazier's points 10 have been assembled so that their broad faces 12 are in abutment substantially throughout. The bodies of the points are not arranged symmetrically with relation to any line perpendicular to faces 12, but are arranged symmetrically relatively to an imaginary plane 14, which is determined by the side edges of each of the points, and which is obliquely disposed relatively to faces 12, and of course similarly obliquely disposed to the mean plane of the points. In this manner, the edges 16 of the points are brought into such relation that, on one side of each point, it overlaps an adjacent point and is overlapped by a point on the opposite sides, while at the 45 other side of the point, the reverse status of the overlapping points is found.

50 In those cases where the edge faces 18 of such points are planar, the planes thereof being substantially perpendicular to the planes of faces 12, and even in such cases where a substantial rounding of edge faces 18 occurs, marked pockets 20 are produced by the disposition and overlapping of the points in the manner set forth. Such pockets provide increased surface with which may cooperate an adhesive material 22, which may be of any particular or desired composition. When such adhesive material is applied along edge faces 18, due to the increased surface with which the adhesive 22 may now cooperate, there is secured a firm and positive bonding of the points to each other, until their separation is desired.

55 While in Figs. 1 and 2, points of diamond shape have been shown, it is easily understood that points of triangular contour might also be arranged in the manner described, in which case, only three edge faces would be dealt with in securing the desired pockets. The result, however, would be substantially identical, and, therefore, is not herein shown.

70 75 75 In Figs. 3 and 4, the invention has been shown

as applied to securing devices such as brads, pins, or similar elements, which are substantially of T-cross-section. In arranging devices of this character to effect the purposes of the invention, it is desirable that some surface of each device be formed in such manner that it may be positioned in contact with a supplementary surface of an adjacent device, in order that the devices be held firmly in desired relationship. In any case, however, the side edges of the devices are intended to be formed in the manner above set forth, that is, substantially planar, or rounded, consisting of a plurality of faces, the planes of the edge faces, when the devices have planar edge faces, being disposed substantially perpendicularly to the mean plane of the body of such devices.

10 15 20 25 30 35 40 45 50 In the construction shown in Figs. 3 and 4, the brad 24 is seen to consist of a head 26 having a nail or tine portion 28 extending therefrom. Head 26 is itself substantially rectangular in its extent, having the side faces 30 substantially parallel to each other, and the edge faces 32 formed as above stated. The brads are disposed so that adjacent units are contiguous throughout at their side faces; the edge faces 32, however, are not within the same plane, although a plane may be so related to said edge faces so that at least lines in each of the faces will be contained in such a common plane. Such plane, however, would be obliquely disposed relatively to any plane which would be perpendicular to any face 30.

55 60 65 70 75 80 85 90 95 In the apparatus shown in Figs. 5 to 12, a construction similar to that illustrated and described in my copending application is disclosed. However, the construction herein is modified to provide means for driving, or otherwise positioning, securing devices, of the character herein set forth, substantially in the manner described for the apparatus in my co-pending application. While the apparatus herein is described in relation to the driving of staples such as shown in my co-pending application, it is, however, to be understood that, by changes within the scope of the ordinary mechanic, such apparatus could be designed to drive glazier's points, or brads, or other securing devices of the kind dealt with in this application, in substantially the same manner as would be involved in the driving of staples.

90 95 Apparatus 34 is seen to comprise a base 36, which may be formed in any well-known manner. It is here shown as made up from a metal stamping, from which have been punched ears 38. The ears are turned upwardly from the base 55 at opposite sides thereof to receive, through openings therein, a pin 40 upon which the body 42 of the apparatus is pivotally mounted.

100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870

70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870

welded, or in any other manner secured to the body to retain the same firmly anchored relatively to the body. The forward ends of both the body 42 and member 48 are cut off in a plane disposed to the longitudinal extent of the body and member at an angle substantially the same as that of the disposition of the planes of assembled staples, or like elements, relative to a plane having a common relation to all of the 10 elements, as seen in Fig. 6.

The flanges 50 provide a runway along which a pusher 52 may slide. The pusher consists of a U-shaped member 54 which is retained between the walls of the body 42 and of the member 48, 15 and the flanges 46 and 50. The forward end of the U-shaped member is intended to engage against staples or similar devices straddling the flanges 50, and is cut off at an angle substantially the same as that in the case of body 42 20 and member 48. Through slot 56 in the upper cross-piece of member 54 is extended down into the groove of member 48 a finger 58. The portion of the finger 58 received within the groove is but slightly smaller than the groove to permit 25 free movement of the finger longitudinally along the groove. By means of a pair of notches 60 in the finger, at the point that the latter passes through slot 56, the finger is retained assembled upon the pusher, and is permitted slight oscillation laterally.

The finger, after it passes above the member 54, is bent rearwardly and so that it is closely adjacent the top surface of member 54. At its rear end the finger is bent upwardly to provide 35 a finger piece 62, the rear end of the finger being retained beneath the lip 64, struck from the metal of member 54 and extending forwardly therefrom. The finger is thus retained for limited oscillation while the finger piece is disposed 40 for cooperation with the fingers of an operator. The body of the finger, immediately at the finger piece, is cut away to leave a portion of the finger piece forming a tooth 66 which is intended to cooperate with a tooth 68, formed by cutting 45 away a portion of a flange 46 of the member 42.

A leaf spring 70, which passes beneath pin 40 and is retained in position relatively thereto by seating within a notch 72 in such pin, is bent upwardly and into abutment with the bottom face 50 of the body and then through an opening in such face, to pass within the groove of the body and position an end wall 76 at the rearmost portion of the body. A coiled spring 78 is retained within the groove of member 48 and presses against 55 the end wall 76 and finger 58, tending to force the pusher against a clip 80 of associated staples such as those described in my copending application aforesaid, or against clips of closures, points or brads, assembled in substantially the 60 same manner.

At the forward end of body 42, there is mounted the vertically extending guide sleeve 82, of sheet metal or similar material, bent to substantially rectangular contour, the lower end of the sleeve 65 being cut and bent away from the body thereof, to provide a pair of tongues 84, receivable around the body 42, to which it may be secured in any well-known manner, such as tack-welding.

Within the passage provided by sleeve 82 is 70 reciprocable a plunger 86, formed, in like manner, of sheet metal, bent into substantially rectangular shape and of such dimensions as to fit substantially snugly within the passage through sleeve 82. The sleeve and the plunger, while each 75 is formed substantially rectangular, each has the

respective forward walls 88 and 90 thereof disposed in such relation that, when the sleeve and plunger are assembled on the body, the planes of these walls will be the same as, or parallel to, the planes of the end edge of body 42 and members 48. 5

One or more nubs 92, pressed or otherwise formed in the outer surface of plunger 86, are provided to retain upon the plunger the driver 94. The latter is secured to the forward face 10 of wall 90 so as to be retained in fixed relation, and substantially parallel to the end edge of body 42, for purposes hereinafter appearing.

The upper end of the plunger is closed by a handle or knob 96, formed in any well-known 15 manner, the handle providing an abutment for a spring 98, housed within the plunger and the sleeve, and bearing against a wall 100, formed by bending inwardly a portion of the metal at the lower end of sleeve 82. 20

In order to retain the plunger in assembled 25 relation with sleeve 82, a resilient member 102 is anchored under a struck out portion 104 on the outside face of the guide sleeve, and is then bent to extend upwardly and then through an opening 106, in the sleeve and within a slot 108 cut through the plunger metal. The spring is then bent outwardly to provide a retaining finger 110 in contact with the outer face of sleeve 82. The portion 112, which engages within slot 108, 30 serves as a stop, limiting upward movement of the plunger. By manipulating finger 110, the interengagement of the portion and the slot may be destroyed so that the plunger may be removed from within the sleeve 82. 35

The driver 94 is substantially only of sufficient thickness to engage against a single staple of the clip 80, which, by the action of spring 78 and the pusher 52, will have been positioned in abutment with the end wall 114, such end wall being secured to the sleeve in any well-known manner. 40 The driver and the end wall are so dimensioned as to be in immediate sliding contact in order to permit efficient engagement of the driver end with but a single staple when the latter is positioned in abutment with the end wall. 45

In this embodiment of the invention, the end wall is formed as a pivoted closure, mounted upon a pin 116, which is supported upon a bracket 118, secured to the outer face of the sleeve. A spring 120 normally tends to rotate the end wall into abutment with the end face of body 42, the forward wall 88 of the sleeve being cut away to permit this. A spring finger 122, in this case the end portion of the end wall, is thereby brought into frictional and interlocking engagement with a pin 124, mounted upon a bracket 126, similar to bracket 118, and at the opposite side of the sleeve. In this manner, the end wall is permitted to be swung away from the body 42, and clips 50 of staples may be loaded into the device merely 55 by sliding them over the flanges 50 of member 48, after the pusher has been retracted, and is so held. 60

In some cases where a staple has been separated from its clip by the action of the driver, but movement of the driver, to close the staple about the material with which it is desired to assemble it, has not been completed, it is necessary to have apparatus related to the driver so 65 that the staple, which has thus been separated, will be returned to its position and held ready for the next succeeding operation. This apparatus also is operative, in case a single staple 70 is fed down through the apparatus and requires 75

support across the groove formed by the spacing at the end face of body 48 relative to the end wall 114. The apparatus for this purpose consists of a metallic U-shaped portion 128, providing a pair of ears 130, between which may be positioned a pivot pin 132 to carry a leaf 134. The forward end of the leaf is cut off at substantially the same angle as the end angles of body 42 and member 50. A coil spring 136 is mounted upon the pin and acts against portion 128 and leaf 134 normally to force the latter away from the portion.

To assemble the portion, it is slipped through the open end of the member 48, as made accessible by swinging the end wall 114 away from body 42, and is locked in place by bringing the base 138 of portion 128 against a pair of stop lugs 140, stamped up from member 48 and against the bent end edge 142 of such member. So located, the leaf will be driven upwardly by its spring and will be brought into abutting relation with the upper edge of an opening 144 in end wall 114. Normally, therefore, the leaf will be in a position to support any free staple which may be fed into the spacing between body 42 and end wall 114.

As the driver moves downwardly against the staple, which, as can be seen, will be carried by leaf 134, the leaf will be pivoted downwardly until the fastening operation has been completed, at which point the staple will have completely cleared the end edge of the leaf.

In order to cooperate with the driver and to effect efficient clinching of the staple, there is provided within a recess 146, formed in the base 36 by spinning the metal, or by any other suitable method, a reciprocable wall 148. The wall is retained normally in raised position by a spring 150, bearing thereagainst, and against a bottom 152, pressed or otherwise inserted into the opening formed in the construction of the recess.

Diametrically of the upper face of the wall a slot 154 is formed by punching or in any other manner bending the metal of the wall downwardly, to provide a pair of oppositely disposed flanges 156 upon which are pivoted the anvil members 158. These members depend downwardly within the slot and bear against a movable base 160, housed within wall 148. Base 160 also provides a housing for a spring 162, which bears against the base and against the bottom 152, to force the former into contact with members 158. The spring 162 is weaker than spring 150 so that when a staple is driven against members 158 by driver 94, the movable base will first be depressed so that the members will be extended downwardly and their curving surfaces 164 will provide a gradually sloping surface for initiating slow bending of the staple teeth. However, as the driver further moves the staple downwardly, and comes into firmer contact with material disposed so that the staple will penetrate the same, substantially direct contact between the driver, the anvil members 158 and the wall 148 is effected, so that the latter is driven downwardly against the action of spring 150, until the wall seats against bottom 152, whereupon the surfaces 164, which are now curving substantially horizontally, as against their vertical disposition, will complete the clinching of the staple legs.

Reciprocable wall 148 is retained against movement within recess 146 by the interengagement of a pair of lugs 166 and slots 168. These lugs and slots are turned so as to retain the slot 154 substantially parallel to the plane of the driver 94, and therefore of the staple driven thereby.

Many other changes could be effected in the articles of manufacture and the apparatus designed, and in the methods of operation set forth, and in the specific details thereof, without substantially departing from the invention hereof, which is intended to be defined in the accompanying claims, the specific description hereinabove carrying out the spirit of the invention.

What is claimed as new and useful is:

1. As an article of manufacture, a series of 10 distinct fastening elements retained bonded together, each of the elements being easily separable from the series, the elements consisting of plates substantially uniform in dimensions, the plates being of substantially uniform thickness throughout and being arranged in the series with plate faces in contact but the faces being laterally displaced, the laterally displaced side edges defining, between pairs, pockets for the reception of an adhesive substance to bond the elements together.

2. As an article of manufacture, a plurality of 15 identical securing devices bound into a unitary assembly, the devices being intended to be driven vertically when made effective for performing the 20 securing function, the devices, in the assembly, being arranged consecutively in contact with each other and being vertically disposed, but being displaced laterally so that a vertical plane 25 intersecting each device at an identical line will not be perpendicular to the contiguous faces of 30 each of the devices.

3. As an article of manufacture, a plurality of 35 identical securing devices bound into a unitary assembly, the devices being intended to be driven vertically when made effective for performing the 40 securing function, each of the devices being a plate of substantially uniform thickness, the devices, in the assembly, being arranged consecutively in contact with each other and being vertically disposed, but being displaced laterally so that a vertical plane intersecting each device at an identical line will not be perpendicular to the 45 contiguous faces of each of the devices.

4. As an article of manufacture, a plurality of 50 identical securing devices bound into a unitary assembly, the devices being intended to be driven vertically when made effective for performing the 55 securing function, each of the devices being a plate of substantially uniform thickness, the devices, in the assembly, being arranged consecutively with the plate faces of immediately contiguous devices in contact with each other, the devices being vertically disposed but being displaced laterally so that a vertical plane intersecting each device at an identical line will not be perpendicular to the 60 contiguous faces of each of the devices.

5. As an article of manufacture, a plurality of 65 identical securing devices bound into a unitary assembly, the devices being intended to be driven vertically when made effective for performing the 70 securing function, each of the devices being a plate of substantially uniform thickness, the other dimensions of the plate being many times greater than the thickness, the devices, in the assembly, being arranged consecutively with the plate faces of immediately contiguous devices in contact with each other, the devices being vertically disposed but being displaced laterally so that a vertical plane intersecting each device at an identical line will not be perpendicular to the 75 contiguous faces of each of the devices.

6. As an article of manufacture, a plurality of 75 identical securing devices bound into a unitary

assembly, the devices being intended to be driven vertically when made effective for performing the securing function, each of the devices being a thin plate of substantially uniform thickness,

5 the devices, in the assembly, being arranged consecutively with the plate faces of immediately contiguous devices in contact with each other, the devices being vertically disposed but being displaced laterally so that a vertical plane intersecting each device at an identical line will not be perpendicular to the contiguous faces of each of the devices.

7. As an article of manufacture, a plurality of identical securing devices bound into a unitary assembly, the devices being intended to be driven vertically when made effective for performing the securing function, each of the devices being a polygonal plate of substantially uniform thickness, the devices, in the assembly, being arranged consecutively with the plate faces of immediately contiguous devices in contact with each other, the devices being vertically disposed but being displaced laterally so that a vertical plane intersecting each device at an identical line will not be perpendicular to the contiguous faces of each of the devices.

8. As an article of manufacture, a plurality of identical securing devices bound into a unitary assembly, the devices being intended to be driven vertically when made effective for performing the securing function, each of the devices being a polygonal plate of substantially uniform thickness, the other dimensions of the plate being many times greater than the thickness, the devices, in the assembly, being arranged consecutively with the plate faces of immediately contiguous devices in contact with each other, the devices being vertically disposed but being dis-

placed laterally so that a vertical plane intersecting each device at an identical line will not be perpendicular to the contiguous faces of each of the devices.

9. As an article of manufacture, a plurality of identical securing devices bound into a unitary assembly, the devices being intended to be driven vertically when made effective for performing the securing function, each of the devices being a polygonal plate of substantially uniform thickness, the other dimensions of the plate being many times greater than the thickness, the devices, in the assembly, being arranged consecutively with the plate faces of immediately contiguous devices in contact with each other, the devices being vertically disposed but being displaced laterally so that, while the plates still maintain their vertical disposition in the assembly, a vertical plane intersecting each device at an identical line will not be perpendicular to the contiguous faces of each of the devices.

10. As an article of manufacture, a plurality of identical securing devices bound into a unitary assembly, the devices being intended to be driven vertically when made effective for performing the securing function, each of the devices being a thin polygonal plate of substantially uniform thickness, the devices, in the assembly, being arranged consecutively with the plate faces of immediately contiguous devices in contact with each other, the devices being vertically disposed but being displaced laterally so that, while the plates still maintain their vertical disposition in the assembly, a vertical plane intersecting each device at an identical line will not be perpendicular to the contiguous faces of each of the devices.

LOU OBSTFELD.
